CALCULATING MACHINE

Herbert E. Brown, Detroit, Mich., assignor to
 Burroughs Adding Machine Company, Detroit,
 Mich., a corporation of Michigan

Application April 5, 1937, Serial No. 134,992

6 Claims. (Cl. 197—128)

This invention relates to the paper equipment or mechanism for business machines and more particularly to an auxiliary paper carriage which will both tabulate to various columnar positions and line space, and is especially adapted to handle postal cards for printing public utility bills.

At the present time most public utility bills which are sent to the various consumers are printed on long sheets of paper and in the same printing operation a duplicate carbon copy is made on a journal or record sheet which is kept by the utility company. This printing is ordinarily done in a long continuous single horizontal line, thereby necessitating a long bill sheet. These long sheets must be folded and inserted in envelopes for mailing which operations incur additional expenses and further necessitates the use of an envelope, thereby involving increased postage as compared with a penny postal card. However, because of its limited size it was impossible to use the penny postal card with paper equipment heretofore constructed and still maintain the conventional manner of posting to a journal or record sheet in a continuous single horizontal line without withdrawing the card and reinserting the same at such a position that some of the printed matter could be printed in a second line on the card while the printing was continued along the same single horizontal line on the carbon record sheet.

Therefore, it is an object of my invention to provide an auxiliary paper carriage which will support a sheet or card independently of a journal or record sheet and which will tabulate to various columnar positions and will line space at desired times.

Another object is the provision of an auxiliary paper carriage which will line space independently of the traveling paper carriage.

Another object is the provision of an auxiliary paper carriage which is independent of the regular paper carriage but controlled by the same to tabulate to various columnar positions and which will line space at a desired time independently of the regular paper carriage.

A further object is the provision of an auxiliary paper carriage which is adapted to tabulate to various columnar positions and to line space independently of the regular paper carriage, so that in the same printing operation, a record may be made in a single horizontal line on a journal or record sheet carried by the regular paper carriage and in a plurality of horizontal lines on a card of limited size carried by the auxiliary carriage.

A still further object is the provision of an auxiliary paper carriage which is adapted to handle postal cards in the printing of public utility bills.

Other objects and advantages of the invention will be made apparent hereinafter.

The nature of the invention will be more apparent from the following specification taken with the accompanying drawings in which one embodiment of my invention is illustrated. The invention is illustrated and described as being applicable to a combination calculating and type-writing machine of the type disclosed in the Hopkins Patent No. 1,336,904, although it will be understood as being applicable, as an auxiliary carriage, to the entire general class of business machines of which the above machine is but one form.

In the drawings:

Figure 1 is a perspective view of a portion of a machine of the type shown in the above Hopkins patent having an auxiliary carriage constructed in accordance with this invention and supported by the regular paper carriage, the auxiliary carriage and the regular paper carriage being at their right-hand positions where printing may be done in column 1, line 1 of the form;

Fig. 2 is a plan view of the auxiliary paper carriage in position so that printing may be done in column 1, line 2 of the form; and

Fig. 3 is a sample of the work performed on the card or sheet carried by the auxiliary carriage.

Referring to Fig. 1 of the drawings, there is illustrated the usual paper carriage 10 which supports a rotatable platen 11 about which are spring clips 12 for holding a carbon and a journal or record sheet upon which a continuous record of the bills of the customers of the utility company is printed. The carriage 10 is of the conventional type shown in the heretofore mentioned Hopkins patent and is tabulated into columnar positions from the right to the end of the line at the left. The platen is also rotated for line spacing the journal or record sheet as shown in the aforesaid patent.

In accordance with my invention an auxiliary postal card carriage 14 is provided. This carriage is independent of the regular carriage 10, although it is actuated and automatically controlled thereby to horizontally tabulate and skip tabulate to different columnar positions, and to line space as desired as will be described hereinafter. The auxiliary card carriage 14 is positioned under the regular carriage 10 and comprises a flat metal plate 15 having an opening 15a and a cut away 55

portion 15^b under the platen 11 to permit the ribbon R, which extends in horizontal position under the platen and under the plate 15, to contact a work sheet or postal card 16 when the type members 17 (Fig. 2) are actuated upwards against the platen 11.

Affixed to the upper surface of plate 14 forward of the platen 11 is a chute 18 which is constructed to receive and guide a card over the plate 14 and under the platen to printing position. The throat 18 is preferably formed of sheet metal and has a top cover or wall 19, which is curved upwardly at the central portion as at 19^a to facilitate the insertion and withdrawal of the card by providing more finger room for the operator, guiding side walls 20 spaced downwardly, curved walls 21 and a bottom supported by legs 22 riveted or otherwise fastened to the plate 15. At the rear of the throat adjacent the plate 15 and the platen 11 is a shaft 24 carried by the guiding side walls 20 and adapted to guide the card 16 into printing position under the platen 11 and to hold it down against the plate 15. Provided at the rearward edge of the plate 15 behind the platen 11 are two upturned lugs 26, extending in the direction of the throat 18, for limiting the rearward movement of the card and for holding rear edge of the same down in proper printing position against the plate 15.

Thus, to place a card in printing position, it is first inserted in the throat 18 and then pushed downwardly and rearwardly under the shaft 24 until it engages the lugs 26 and overlies openings 15^a and 15^b. The card is then in proper printing position where it is frictionally maintained because of the fact that the rear portion of the card is held down by the shaft 24 and the lugs 26, and the front portion is bent slightly upward because of the curvature of the bottom guides 21 and 22.

The card carriage 14 is supported upon a rail 28, having an inverted T-shaped channel 29 in which slide headed studs 30 project from the under side of the plate 15. Rail 28 thus provides a definite horizontal guide controlling the horizontal sliding movement of the plate to the left when tabulating to different columnar positions. Rail 28 is preferably supported from the top plate 36 by means of brackets 32 which are fastened to the top plate 36 at its right and left sides. The brackets 32 provide a sliding bearing for rail 28 as it is moved horizontally during tabulating movement. There are further provided lugs 32^a also supported by the top plate 36 and which overlie rearwardly extending arms 28^a and 43^a near the ends of the rail 28. The lugs 32^a prevent the rail 28 from moving upwardly so as to interfere with the traveling paper carriage. A spring 33 secured under tension between a stud 34 located on the left front portion of the under surface of plate 15 and a stud 35 located at the right side of the stationary top plate 36 of the machine constantly urges the plate 15 to its normal position at the extreme right. Movement of the plate 15 to the right is limited and cushioned by a bumper 37 on the right end portion of the rail 28.

In order that the auxiliary carriage 14 may tabulate to the left along with the usual traveling paper carriage 10, a rail 38 at the forward edge of the traveling carriage is provided with a bracket 39 carrying a pivoted dog 40 urged clockwise by a tension spring 41 connected to the bracket 39 and the dog 40. Dog 40 has a turned down edge portion 40^a for engagement with a stud 42 carried by the plate 15 by which tabulating

movement of the carriage 10 is imparted to the plate 15. Thus, as the machine is operated to print in different columnar positions, the carriage 10 tabulates from the right to the left and causes the auxiliary carriage plate 15 also to tabulate to the left on the rail 28, so that when amounts are printed on the card 16 carried by the plate 15, a duplicate is produced on the record or journal sheet carried by the paper carriage 10. It will thus be seen that the plate 15 and the regular 10 paper carriage 10 tabulate as a unit although independent of each other and that when the regular carriage tabulates or skip tabulates to various columnar positions, the card plate 15 will do likewise.

Although the transaction is printed in a single continuous horizontal line on the record or journal sheet, it is not possible to print the same in a single horizontal line on the card 16 because of its relatively narrower width. Therefore, I have provided a mechanism, which I shall describe hereinafter, by which the card may be line spaced following partial entry of the transaction and the remainder of the transaction printed in a second line thereon in spaced columnar positions. The rail 28, along which plate 15 tabulates, is provided at its right end with an arm 43 and adjacent its left end by another arm 44, which arms are pivotally connected to the rearward ends of cranks 45 and 46 as at 47 and 48, the cranks 30 being pivoted to the top plate 35 at 49 and 50, respectively. A connecting bar or link 51 is also pivotally attached to the forward ends of the cranks 45 and 46 as at 52 and 53. A tension spring 55 connected to a fixed pin 56 on the top plate 36 and to the forward arm of the crank 45, normally urges the crank 45 and also the crank 46, by operation of the bar 51 to the left, in a clockwise direction. Accordingly, the rail 28 which carries the plate 15 is constantly urged in a forward direction. However, a latch 57 carried by the bar 51 adjacent its left end and pivoted thereto at 57^a, limits the forward movement of the plate 15 and rail 28 by engaging a stud 58 on the upper surface of the rearward arm of the crank 46. The latch 57 is cut away or recessed as at 59 to receive the stud 58, and a spring 54, under tension between the rail 51 and the right arm of the latch 57, constantly urges the latch in a clockwise direction into contact with stud 58. Therefore, the plate 15 is normally held in rearward position while tabulating from right to left during the printing of the first line of the transaction on the card, although it is constantly urged forwardly by spring 55.

After printing in the last column of the first line on the card has occurred and the carriage 10 is further tabulated, a roller 60 carried by the rail 38 engages a pointed end 61 of the latch 57 and rocks the latch counterclockwise to disengage the latch from stud 58, which permits spring 55 to rock the cranks 45 and 46 in a clockwise direction with the result that the rail 28 and the plate 15 are moved to a forward position. By this forward movement, stud 42 is carried forward and disengaged from the dog 40 so that the plate 15 is free to return to the right under influence of spring 33. Movement to the right is limited, however, by the engagement of a rearwardly and downwardly extending lug 62, 70 projecting from bracket 39, with a stud 63, positioned on the left front portion of the plate 15. In this position the postal card carried by the plate 15 is under the right portion of the journal sheet and is ready for printing in the first column 75

of the second line while the regular carriage with the platen carried thereby is in position to continue on a single line of posting on the journal or record sheet. Thus, when roller 60 rocks the latch 57, the aforescribed mechanism moves the plate 15 forward for second line printing and at the same time returns it to the right for column one printing, this position being shown in Fig. 2.

As the regular carriage 10 continues to tabulate to the left, the plate 15 also tabulates to the left, against the action of spring 33, to the same columnar positions because of the engagement of the stud 63 of the plate 15 with the lug 62 of the carriage 10, and the amounts are printed on the second line of the card. After the last amount has been printed on the second line of the card and the single horizontal line of the journal sheet, the regular carriage 10 is returned to the right by motor power (not shown) thereby allowing the plate 15 to slide to the right along rail 28 under the urge of the spring 33.

When the regular carriage 10 and the auxiliary carriage 14 are returning to their initial right-hand positions, the carriage 14 is still in forward, line two printing position, and, therefore, I have provided means for mechanically returning the auxiliary carriage, plate 15, to its initial rearward, line one printing position. This means consists of a forwardly extending lug 64 carried by the front rail 38 of the regular carriage 10 which engages an upstanding lug 65 of the connecting bar 51 when the carriage 10 is moved to the extreme right. The bar 51 is thereby moved to the right to rock the arms 45 and 46 in a counterclockwise direction against the action of spring 55 and thus causes the rail 28 and the plate 15 to move rearwardly into line one printing position, where it is retained by latch 57. At this time, after the finished card is removed, a new blank card may be inserted in the throat and the operations again repeated.

Although the foregoing description has set forth one form of auxiliary card carriage as applied to one type of calculating machine, it will be apparent that the invention may be applied to different types of business machines. It will also be understood that changes and other modifications may be resorted to without departing from the spirit and scope of the invention as defined in the appended claims.

I claim:

1. In combination with a business machine, a traveling paper carriage, means thereon for supporting a record sheet in printing position, an auxiliary paper carriage, means thereon for supporting a work sheet in printing position, means for supporting said auxiliary paper carriage on the machine independently of the traveling paper carriage, said auxiliary paper carriage being adapted for tabulating movement with said traveling paper carriage and for line spacing movement independent of line spacing movement of said record sheet, means for causing said auxiliary paper carriage to tabulate automatically with the traveling paper carriage to position said work sheet for printing in various columns thereon, means acting automatically in a predetermined position of said traveling paper carriage for line spacing the auxiliary paper carriage and work sheet thereon to second line printing position without line spacing movement of said record sheet, and means automatically operable after said line spacing movement for causing said auxiliary paper carriage again to move with the traveling paper carriage in tabulating direction

for printing in the different columnar positions of said work sheet.

2. In combination with a business machine, a traveling paper carriage, means thereon for supporting a record sheet in printing position, an auxiliary paper carriage, means thereon for supporting a work sheet in printing position, means for supporting said auxiliary paper carriage on the machine for movements in tabulating or return direction and movement in line spacing direction independently of movements of the traveling paper carriage, said auxiliary paper carriage also being adapted for tabulating movement with said traveling paper carriage, means for causing said auxiliary paper carriage to tabulate automatically with the traveling paper carriage to position said work sheet for printing in various columns thereon, means acting automatically in a predetermined position of said traveling paper carriage for line spacing the auxiliary paper carriage and work sheet thereon to second line printing position without line spacing movement of said record sheet, means operating automatically in said column for causing said auxiliary carriage to return to initial columnar position, means automatically operable after said line spacing and return movement of said auxiliary carriage for causing said auxiliary paper carriage again to move automatically with the traveling paper carriage in tabulating direction for printing in the different columnar positions of said work sheet, and means for causing the auxiliary paper carriage to return to initial printing position upon the return of said traveling paper carriage.

3. In combination with a business machine, a traveling paper carriage, means thereon for supporting a record sheet in printing position, an auxiliary paper carriage, means thereon for supporting a work sheet in printing position, means for supporting said auxiliary paper carriage on the machine independently of the traveling paper carriage, said auxiliary paper carriage being adapted for movement in tabulating direction with said traveling paper carriage and in line spacing direction independent of line spacing movements of said record sheet, means for causing said auxiliary paper carriage to tabulate automatically with the traveling paper carriage to position said work sheet for printing in various columns thereon, means acting automatically to line space said auxiliary paper carriage and work sheet thereon without line spacing movements of said record sheet after a predetermined number of tabulating movements of said paper carriage, means for preventing line spacing of the auxiliary paper carriage, means for releasing said preventing means, means operable after operation of said releasing means for causing said auxiliary paper carriage again to move automatically in tabulating direction with the traveling paper carriage, and means for causing the auxiliary paper carriage to return to initial printing position.

4. In combination with a business machine, a traveling paper carriage, means thereon for supporting a record sheet in printing position, a rail mounted on said machine independently of the traveling paper carriage, a plate mounted on said rail, means mounted on said plate adapted to receive and hold a card in printing position, connecting means between said plate and the traveling paper carriage by which tabulating movements of the traveling paper carriage are imparted to said plate to cause it to move in tabulating direction along the rail with said

- traveling paper carriage to position said card for printing in various columnar positions thereon, means automatically operable in a predetermined columnar position of said plate for line spacing said plate to second line printing position and for returning said plate to initial columnar position without movements of said record sheet, means for maintaining said plate in first line printing position, means for releasing said latter means after predetermined tabulating movements of said traveling paper carriage, and additional connections between said plate and the traveling paper carriage operable after operation of said releasing means for imparting further tabulating movements of the traveling paper carriage to said plate in second line of printing to cause it to position the card thereon for printing in various columnar positions thereon.
5. In combination with a business machine, a traveling paper carriage, means thereon for supporting a record sheet in printing position, a rail mounted on the machine independently of the traveling paper carriage, a plate mounted on said rail, means mounted on said plate adapted to receive and hold a card in printing position, connecting means between said plate and the traveling paper carriage by which tabulating movements of the traveling paper carriage are imparted to said plate to cause it to move in tabulating direction along the rail with said traveling paper carriage to position said card for printing in various columnar positions thereon, means acting automatically for causing line spacing movement of said rail to line space said plate to second line printing position without line spacing movements of said record sheet, means for maintaining said rail in first line printing position, means for releasing said latter means after predetermined tabulating movements of said traveling paper carriage, additional connections

between said plate and the traveling paper carriage operable after operation of said releasing means for imparting further tabulating movements of the traveling paper carriage to said plate to cause it to position the card thereon for printing in various columnar positions thereon, and means acting automatically for causing said rail and plate to return to initial printing position when said traveling paper carriage is returned.

6. In combination with a business machine, a traveling paper carriage, means thereon for supporting a record sheet in printing position, an auxiliary paper carriage, means thereon for supporting a work sheet in printing position, means for supporting said auxiliary paper carriage on said machine for movement in tabulating and return directions and for line spacing movement independently of such movements of said record sheet, said auxiliary paper carriage also being adapted for tabulating movement with said traveling paper carriage, means for causing said auxiliary paper carriage automatically to move in tabulating direction with the traveling paper carriage to position said work sheet for printing in various columns thereon, means acting automatically in a predetermined position of said traveling paper carriage for causing line spacing movement of said auxiliary carriage supporting means to line space the auxiliary carriage and work sheet thereon to second line printing position without line spacing movement of said record sheet, means also acting automatically in said column for causing return movement of said auxiliary carriage to initial columnar position, and means automatically operable after said line spacing and return movements for causing said auxiliary paper carriage again to move with the traveling paper carriage for printing in the different columnar positions of the work sheet.

HERBERT E. BROWN.
